DESIGN FOR A LACE

Max Solomon, New York, N. Y.

Application June 9, 1936, Serial No. 63,171

Term of patent 3½ years

To all whom it may concern:

Be it known that I, Max Solomon, a citizen of the United States of America, residing in the city of New York, county of New York, and State of New York, have invented a new, original, and ornamental Design for a Lace, of which the following is a specification, reference being had to the accompanying drawing, forming part thereof. The figure of the drawing is a plan view of a lace embodying my new design.

The design unit is contained between the broken lines, which unit is repeated in regular succession as indicated by the extensions beyond the unit boundaries.

I claim:

The ornamental design for a lace, substantially as shown and described.

MAX SOLOMON.
